UNITED STATES PATENT OFFICE.

LOSSIE CASTEEL, OF MARION, IOWA.

GRAIN-DOOR FOR CARS.

No. 802,973.

Specification of Letters Patent.

Patented Oct. 31, 1905.

Application filed December 30, 1904. Serial No. 238,996.

To all whom it may concern:

Be it known that I, LOSSIE CASTEEL, a citizen of the United States, residing at Marion, in the county of Lynn and State of Iowa, have 5 invented certain new and useful Improvements in Grain-Doors for Cars, of which the following is a specification.

This invention aims to provide a simple construction of door particularly designed for 10 freight-cars; and the principal object of the invention is to provide a door structure of great strength and durability and one which will afford a closure for freight-cars or the like which will reduce the shrinkage of grain 15 which may be transported therein to a minimum.

For a full description of the invention and the merits thereof and also to acquire a knowledge of the details of construction of the 20 means for effecting the result reference is to be had to the following description and accompanying drawings.

While the invention may be adapted to different forms and conditions by changes in the 25 structure and minor details without departing from the spirit or essential features thereof, still the preferred embodiment of the invention is shown in the accompanying drawings, in which—

30 Figure 1 is a perspective view showing the invention when in actual use. Fig. 2 is a vertical sectional view. Fig. 3 is a horizontal sectional view. Fig. 4 is a detail view, partially broken away, showing the operation of one of 35 the vertical guides and the U-shaped base-plate.

Corresponding and like parts are referred to in the following description and indicated in all the views of the drawings by the same 40 reference characters.

In illustrating the invention the numeral 1 indicates the sides of a car or similar support, the numeral 2 the frame of a door, and the numeral 3 a door operating in the frame 2. 45 The door 3 is of that type which are mounted so as to admit of vertical and horizontal sliding movement, the vertical movement of the door effecting opening thereof and the horizontal movement carrying the door into a position 50 in which it will be out of the way and not likely to interfere with the introduction or removal of grain. The door 3 is of peculiar structure, being formed with a view to promoting its strength to the greatest extent 55 possible, and for this purpose the body 4 of the door may be made of any suitable mate-

rial, such as wood or the like; but said body is reinforced by means of oppositely-disposed side plates 5, said plates being attached to the body 4 of the door by means of suitable fastenings.

The plates 5 are ribbed or corrugated almost entirely over the surface thereof, and the ribs or corrugations of one side plate 5 extend at an angle to those of the other side plate in 65 order that the central or main portion of the body 4 of the door will be firmly braced from any sagging or bulging action, the above effecting an ease of working the door in its guides upon the door-frame and being otherwise advantageous, as will be readily apparent. Mounted horizontally upon the side 1 of the car, interior thereof and approximately just above the upper extremity of the door-frame 2, is a supporting-bar 7, mounted at 75 its ends in suitable substantial brackets 10. The door 3 is provided with engaging means at the upper portion thereof in the form of coöoperating spring-fingers 11, a pair of which are located adjacent each end of the door, and 80 these fingers have the upper portions thereof flared outwardly from each other, as shown at 12. The door 3 is adapted to be raised and lowered by means of a connection 13, such as a chain or the like, which passes over a pulley 14, 85 swiveled with the door of the car in any suitable manner just above the door-frame 2. The chain or connection 13 connects with a clip 15, secured to the upper portion of the door 3, and when this chain is pulled upon 90 to elevate the door 3 the spring-fingers 11 are engaged with the bar 7, which passes between the flared extremities of said fingers in the upper movement of the door, and the engaging coöperation of the members 11 with the 95 bar 9 is sufficient to hold the door suspended from the bar 9 and adapted for a horizontal movement longitudinally thereof, in order that the door may be pushed to one side and out of the way. When the door 3 is forced to 100 one side of the door-frame 2, it is held in this position preferably by means of a hook 16, attached to the side of the car and adapted to coöperate with an eye member 17, projecting from the inner side of said door. The swiv- 105

eled mounting of the pulley 14 permits this pulley to vary its position, so as to admit of free movement of the connection 13 thereover when the door 3 is being moved vertically or horizontally, as the case may be. The door 110 3 is mounted in suitable guides upon the door-frame when said door is in its normal posi-

tion, and these guides consist, essentially, of angle-plates 18, secured to the said posts of the door-frame 2 adjacent the inner sides of these parts. The angle-plates 18 are attached by any suitable fastenings, and projecting from the inner wings of these angle-plates and preferably integral therewith are angle-webs 19, which are so arranged with reference to the plates 18 as to form vertical guides in which the door 3 is adapted to freely slide in its vertical movement. The angle-webs 19 are firmly braced with reference to the plates 18 by means of horizontal webs 20, which connect the wing of the angle-webs formed with said angle-plates and adjacent portions of the inner wing of said angle-plates. The webs 20 firmly brace the angle-webs 19 when inward pressure is exerted against the door 3 and greatly increase the substantiality of the guides of the door in a manner readily apparent. The lower edge portion of the door is adapted to be received in a U-shaped base-plate 21, attached to the bottom of the car and across the door-frame. The sides of the plate 21 are reinforced by sill-bars 22, the upper sides of which curve downwardly from the upper edge portions of the sides of said plate 21. One of the members 22 is located upon opposite sides of the plate 21, reinforcing this member 21 in a substantial manner. It is also preferred to utilize a sill-plate 23 at the bottom of the door-frame 2, a common means for protecting the car at this portion thereof.

Having thus described the invention, what is claimed as new is—

1. In door construction of the type described, the combination of a door-frame provided with vertical guides at opposite sides thereof, a door mounted in said guides, a swiveled pulley above the door-frame, a connection for elevating the door passing over said pulley and connected with the door, a horizontal bar disposed above the door and of greater length than the width of said door, and members carried by the door for coöperation with the horizontal bar to suspend the door from said bar, whereby the door may be moved longitudinally of the bar away from the door-opening, the pulley adjusting itself to the connection passing thereover when the latter is actuated to pull the door toward the door-opening.

2. In door construction of the type described, the combination of a door-frame, a door, guides for the door comprising the angle-plates 18 attached to the sides of the door-frame, the angle-webs 19 integral with said angle-plates and projecting from one of the wings thereof, and the horizontal webs 20 connecting the angle-webs with the angle-plates.

In testimony whereof I affix my signature in presence of two witnesses.

LOSSIE CASTEEL. [L. S.]
